US0D1099780S

(12) **United States Design Patent** (10) Patent No.: **US D1,099,780 S**
(45) Date of Patent: ** Oct. 28, 2025

(54) **REAR DIFFUSER FOR MOTOR VEHICLE**

(71) Applicant: **Dr. Ing. h.c. F. Porsche
Aktiengesellschaft**, Stuttgart (DE)
(72) Inventor: **Emiel Burki**, Stuttgart (DE)
(73) Assignee: **Dr. Ing. h.c. F. Porsche
Aktiengesellschaft** (DE)

(**) Term: **15 Years**

(21) Appl. No.: **29/915,731**

(22) Filed: **Nov. 3, 2023**

(30) **Foreign Application Priority Data**

May 5, 2023 (EM) 015020634-0015

(51) LOC (15) Cl. **12-16**

CLAIM

The ornamental design for a rear diffuser for motor vehicle as shown and described.

DESCRIPTION

FIG. 1 is a perspective view of a rear diffuser for motor vehicle showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

(Continued)

The broken lines illustrate portions of the rear diffuser for motor vehicle that form no part of the claimed design.

1 Claim, 7 Drawing Sheets
